DESIGN FOR A TOP BAND FOR A HANDBAG FRAME

John De Pasquale and Alexander Westerman,
Brooklyn, N. Y., assignors to Hardy Metal Specialties Inc., Brooklyn, N. Y., a corporation of New York

Application June 5, 1944, Serial No. 113,856

Term of patent 7 years

(CL. D87—2)

To all whom it may concern:

Be it known that we, John De Pasquale and Alexander Westerman, both citizens of the United States, both residing at Brooklyn, in the county of Kings, city and State of New York, have invented a new, original, and ornamental Design for a Top Band for a Handbag Frame, of which the following is a specification, reference being had to the accompanying drawing, forming part thereof.

In the drawing

Fig. 1 is a front elevational view of a top band for a handbag frame, showing my new design;

Fig. 2 is a plan view of the bottom thereof;
Fig. 3 is a sectional view on the line 3—3 of

Fig. 4 is a sectional view on the line 4—4 of Figure 1.

We claim:

The ornamental design for a top band for a handbag frame, substantially as shown.

JOHN DE PASQUALE.
ALEXANDER WESTERMAN.
